(57) **CLAIM**

The ornamental design for a three dimensional mastopexy implant, as shown and described.

DESCRIPTION

FIG. 1 is a front view of a three dimensional mastopexy implant showing our new design;

FIG. 2 is a left side view of the three dimensional mastopexy implant shown in FIG. 1;

FIG. 3 is a right side view of the three dimensional mastopexy implant shown in FIG. 1;

FIG. 4 is a bottom view of the three dimensional mastopexy implant shown in FIG. 1;

FIG. 5 is a top view of the three dimensional mastopexy implant shown in FIG. 1;

FIG. 6 is a rear view of the three dimensional mastopexy implant shown in FIG. 1; and,

FIG. 7 is a top, front, side perspective view of the three dimensional mastopexy implant shown in FIG. 1.

The broken lines shown in the figures form no part of the claimed design.
